Primary Examiner — George D. Kirschbaum
 Assistant Examiner — Antoinette Martine Suiter(57) **CLAIM**

The ornamental design for a laser level as shown and described.

DESCRIPTION

Laser level

1.1: Left

1.2: Right

1.3: Front

1.4: Perspective

1.5: Back

1.6: Perspective

1.7: Perspective

1 Claim, 7 Drawing Sheets
